SCREW TYPE COMMINUTING APPARATUS

Christian Börner, Obernburg (Main), Germany, assignor to Vereinigte Glanzstoff-Fabriken A. G., Wuppertal-Eberfeld, Germany

Application June 24, 1952, Serial No. 295,284

Claims priority, application Germany June 25, 1951

6 Claims. (Cl. 241—276)

The present invention relates to a screw type comminuting apparatus.

More particularly, the present invention relates to a comminuting apparatus of the screw type which is adapted to comminute material by rotation of the screw within a cylindrical enclosure located about the screw.

In devices of this type, particularly those which are used for industrial purposes, it sometimes happens that the material being comminuted becomes tightly squeezed between the screw and cylinder which results in the requirement of an extremely great force to rotate the screw and sometimes results in jamming of the screws so that the latter cannot be turned. These difficulties frequently arise for example in the comminuting of materials such as alkali-cellulose. A further disadvantage of such constructions is that they cause the material being comminuted to become undesirably overheated so that they are not in a suitable condition for the further steps of a given chemical process, or the like.

It is therefore a general object of the present invention to provide a screw type comminuting device with a means for comminuting the material with a force augmenting that of the screw and cylinder so that the material being comminuted will not become jammed or overheated and so that the energy required to rotate the screw will be appreciably diminished.

With this object in view, the present invention mainly consists of a screw type comminuting apparatus which includes an elongated cylinder having an elongated screw located therein spaced from the inner surface thereof, extending along the axis thereof, and being mounted in the cylinder for rotation about this axis. A plurality of pairs of opposite transverse wall members are fixedly connected to the screw between the convolutions thereof to form chambers within these convolutions, and each of these wall members has an outer free surface portion facing the inner surface of the cylinder, spaced therefrom and gradually approaching the latter so as to form a nozzle with the inner cylinder surface so that material being comminuted will be compressed against the latter.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a side sectional, perspective view of an apparatus constructed in accordance with the present invention; and

Fig. 2 is a fragmentary, perspective view of a part of the apparatus of Figure 1.

Referring to the drawings, there is shown in Figure 1 a cylindrical enclosure 1 having at its right upper end, as viewed in Figure 1, an inlet and at its left lower end, as viewed in Figure 1, an outlet. This cylinder 1 is provided with opposite end walls which support, for rotation about

2

the axis of the cylinder 1, a screw member 3 located within the cylinder 1 and being spaced from the inner surface thereof by a gap 6. This inner surface of cylinder 1 is provided with pyramidal teeth 2, as is clearly shown in Figure 1. Between the convolutions of the screw 3 there are provided a plurality of pairs of opposite walls 5, whose construction is most clearly shown in Figure 2, all of the walls 5 on one side of the turning axis of screw 3 terminating in edges which are located along a straight line, and along each of these straight lines there is fixed to the screw member 3 for rotation therewith a toothed strip 4 which cooperates with the teeth 2 to comminute the material, this material first entering the chamber 7 of worm 3 and then successively entering the chambers of worm 3 formed by walls 5.

As is shown most clearly in Figure 2, the walls 5 each have outer surface portions which face the inner cylinder surface of the cylinder 1 and which gradually approach the same to form a nozzle 8 so that, when the screw is turned in the direction of the arrow shown in Figures 1 and 2, the material being comminuted is forced by the outer surface of walls 5 against the inner cylindrical surface to greatly increase the comminuting action of the device so that overheating of the material and jamming of the apparatus is prevented. Also the energy required to operate the apparatus is greatly diminished.

Although these outer surface portions of walls 5, which face the inner surface of cylinder 8 and gradually approach the same, may be flat, in the particular example illustrated, these surfaces are convexly curved.

It will be understood that each of the elements described above, or two or more together, may also find a useful application in other types of screw type comminuting apparatus differing from the types described above.

While I have illustrated and described the invention as embodied in screw type comminuting apparatus for positively compressing the material being comminuted against the inner surface of a casing of the apparatus, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. A screw type comminuting apparatus comprising, in combination, an elongated circular cylinder; an elongated screw of constant radius spaced from the inner surface of said cylinder, extending along the length thereof, and being mounted within said cylinder for rotation about the central axis of the latter; a plurality of transverse walls fixedly connected to said screw between the convolutions thereof, each extending from one convolution to the next convolution and each having a terminal surface portion at the same radial distance from said axis as the screw periphery located adjacent to but spaced from the inner surface of said cylinder and defining a substantially wedge-shaped space with the inner surface of said cylinder to form a nozzle with the latter, said terminal surface portions of said walls also defining with said inner surface of said cylinder a gap having a width which remains constant at all angular positions of said screw during rotation thereof; and projecting

means at the inner surface of said cylinder projecting toward the screw and distributed about said inner surface for participating in the comminuting action of the apparatus, so that material being comminuted within said cylinder during rotation of said screw is compressed against the inner surface of said cylinder and through the gap between the same and said walls so as to be comminuted with a force augmenting that produced by the screw and cylinder.

2. A screw type comminuting apparatus comprising, in combination, an elongated circular cylinder; an elongated screw of constant radius spaced from the inner surface of said cylinder, extending along the length thereof, and being mounted within said cylinder for rotation about the central axis of the latter; a plurality of pairs of opposite, transverse wall members fixedly connected to said screw between and in contact with the convolutions thereof to form separate chambers with said convolutions, each of said wall members having an outer free terminal surface portion at the same radial distance from said axis as the screw periphery facing said inner surface of said cylinder, being spaced therefrom and defining a substantially wedge-shaped space therewith to form a nozzle with said inner cylinder surface so that material being comminuted will be compressed against the latter, said terminal surface portions of said wall members also defining with said inner surface of said cylinder a gap having a width which remains constant at all angular positions of said screw during rotation thereof; and projecting means at the inner surface of said cylinder projecting toward said screw and distributed about said inner surface of said cylinder for participating in the comminuting action of the apparatus.

3. A screw type comminuting apparatus comprising, in combination, an elongated cylinder; an elongated screw spaced from the inner surface of said cylinder, extending along the length thereof and being mounted within said cylinder for rotation about the central axis of the latter; a plurality of pairs of opposite, transverse wall members fixedly connected to said screw between and in contact with the convolutions thereof to form separate chambers with said convolutions, each of said wall members having

an outer free terminal surface portion facing said inner surface of said cylinder, being spaced therefrom and defining a substantially wedge-shaped space therewith so as to form a nozzle with said inner cylinder surface so that material being comminuted will be compressed against the latter, the wall members on each side of said cylinder axis terminating in free edges which are located along a substantially straight line parallel to said axis; and an elongated toothed member fixed to said free edges of said wall members and located at the outer surface of said screw extending across the convolutions thereof.

4. A screw type comminuting apparatus as defined in claim 3 and wherein said inner cylinder surface is provided with a plurality of teeth.

5. A screw type comminuting apparatus comprising, in combination; an elongated cylinder having an inner cylinder surface provided with a plurality of teeth; an elongated screw spaced from the inner surface of said cylinder, extending along the length thereof and being mounted within said cylinder for rotation about the central axis of the latter; and a plurality of pairs of opposite, transverse wall members fixedly connected to said screw between and in contact with the convolutions thereof to form separate chambers with said convolutions, each of said wall members having an outer free terminal surface portion facing said inner surface of said cylinder, being spaced therefrom and defining a substantially wedge-shaped space therewith so as to form a nozzle with said inner cylinder surface so that material being comminuted will be compressed against the latter.

6. A screw type comminuting apparatus as defined in claim 2 and wherein said outer free surface portion of each wall member is convexly curved.
